United States Patent Office.

GEORGE W. JOHNSON, OF DANVILLE, VIRGINIA, ASSIGNOR TO JAMES P. HAWKINS, OF SAME PLACE.

Letters Patent No. 101,883, dated April 12, 1870.

IMPROVEMENT IN TOBACCO-BAGS.

The Schedule referred to in these Letters Patent and making part of the same

To all whom it may concern:

Be it known that I, GEORGE W. JOHNSON, of Danville, in the county of Pittsylvania and in the State of Virginia, have invented certain new and useful Improvements in Tobacco-Bags; and do hereby declare that the following is a full, clear, and exact description thereof, reference being had to the accompanying drawings and to the letters of reference marked thereon making a part of this specification.

The nature of my invention consists in the construction or manner of making tobacco-bags, as will be hereinafter set forth.

In order to enable others skilled in the art to which my invention appertains to make and use the same, I will now proceed to describe its construction and operation, referring to the annexed drawings, in which—

Figure 1 is a side view of my improved tobacco-bag turned wrong side out;

Figure 2 is a side view; and

Figure 3, a bottom view of the same.

I take a piece of muslin, or suitable material, of a suitable size, and bend it over double. I then sew a seam, beginning at the left-hand bottom corner, and after sewing across the bottom pucker it, as shown in figs. 1, 2, and 3, and then tack the lower right-hand corner, and continue the seam with the same thread up the side of the bag to the top.

The top or mouth is then bent over all around, and a thread or string sewed loosely around the part thus bent over, leaving the ends of the string protrude, so that when they are drawn the top of the bag is also pucker, as shown in fig. 2.

The bottom forms a flat surface, as shown in fig. 3, and when the bag is closed both top and bottom appear alike, as shown in fig. 2.

I am fully aware that bags of almost any description have been drawn together by strings at the mouth and form a pucker. Hence, I disclaim such to be my invention.

What I claim, is—

As a new article of manufacture, the within-described tobacco-bag formed of a single piece of muslin folded over and seamed by a single thread down the sides and bottom, with the bottom pucker, and the top pucker by a string sewed around it loosely, all as set forth.

In testimony that I claim the foregoing, I have hereunto set my hand this 18th day of February, 1870.

G. W. JOHNSON.
